John Shull, New Petersburgh - Ohio

Letters Patent.

The schedule referred to in these Letters Patent, and making part of the same, containing a description in the words of the said John Shull himself, of his improvement in the Washing Machine.

To all to whom these presents shall come. Be it known, that I, John Shull, of New Petersburgh, in the County of Highland, and State of Ohio, have invented a new and useful improvement in Machinery for Washing clothes, and that the following is a full and exact description of the construction and operation of said Machine, as invented or improved by me. I make a shaft of about thirty four inches in length and two or three inches diameter, on or near the extremity of which, I affix circular pieces of timber of about twenty inches in diameter. Then make about thirty small arms or rods, with shoulders, being the length of the diameter of the heads of the open cylinder, which does project alternately through the shaft in two rows, at a regular distance from each other, which cross at right angles the ends of which are fastened to the ends of the shaft, - which pieces form four apartments. I then take four pieces of narrow timber, through which make holes sufficiently large to introduce the ends of the rods projecting through the shaft and then make them fast, at each extremity to the heads of the open cylinder. These make four shutters, the length of the shaft, fastened with hinges to four bars or pieces of timber, extending from one end of the open cylinder to the other, & fastened to the four above mentioned bars, through which the rods project, by four bolts, & then

fill up the circumference of the open cylinder with narrow pieces of timber, for the purpose of containing the garments to be washed, and of admitting the water which is introduced into an outer cylinder, constructed so as to be water-tight, and in which the open cylinder is made to revolve upon iron judgons fixed in the ends of the shaft, one of sufficient length to project through one end of outer cylinder so that a cork may be attached by a screw or spike on the end of the judgon. I make the outer cylinder sufficiently large to admit of the open or inner cylinder running clear. The outer or tight cylinder shall be fixed in a frame so constructed as to keep it firm, with an opening sufficiently large to admit clothes for washing, and the opening of the shutter of the inner cylinder.

To prepare clothes for washing soak or wet them in water; introduce them into the open cylinder; fasten the shutter; then add five or six gallons of warm water with sufficiency of soap to produce suds; then closing the shutter of the outer cylinder which fits in such a manner as to prevent the escape of either suds or steam, the latter of which, after having been generated in a small boiler (ay of the capacity of five or six gallons) having over a fire, when being conducted thence by a small tube, admitted into the end of the outer cylinder, through a small aperture, between the centre and top.

I affix a guard upon the end of the horizontal line head of the cylinder, to prevent it interfering with the inner works. The clothes, after having been subjected to the heat of the steam and action of the water (the last being effected by the reception of the pump gland)

a sufficient length of time to prepare them for rinsing, the ends are let off, by means of an aperture in the bottom of the outer cylinder, previously closed by a common stopper, and clean water introduced into the machine, for the purpose of rinsing, which is performed in the same manner as washing. When the clothes are ready to be taken out the safety valve of the boiler being first opened for the escape of the steam, the shutter of the outer and that of the inner cylinders, are successively open and the clothes taken out.

I claim as my invention, the formation of the revolving open cylinder; and the introduction of the steam into the same, in the manner described.

Witnessed
